(57) **CLAIM**

The ornamental design for a mount for electronic devices, as shown and described.

DESCRIPTION

FIG. 1 is a front, side, and top perspective view of a mount for electronic devices embodying the new design;

FIG. 2 is a back, side, and bottom perspective view thereof;

FIG. 3 is a front view thereof;

FIG. 4 is a back view thereof;

FIG. 5 is a top view thereof;

FIG. 6 is a bottom view thereof; and,

FIG. 7 is a first side view thereof, the second side view being a mirror image.

The broken lines form no part of the claimed design. The broken lines depict portions of the mount for electronic devices in which the claimed design is embodied and form no part of the claimed design.
